United States Patent Office

Des. 178,155
Patented June 26, 1956

178,155

ROOM COOLERS

Frank D. Stevens, Syracuse, N. Y., assignor to Carrier Corporation, Syracuse, N. Y., a corporation of Delaware

Application June 1, 1955, Serial No. 36,331

Term of patent 3½ years

(Cl. D62—4)

The other side of the room cooler forming the subject of this invention is similar to the side shown.

I claim:

The ornamental design for a room cooler, as shown and described.
